PICKLING APPARATUS

Walter D. Keller, Alliance, Ohio, assignor to The Alliance Machine Company, Alliance, Ohio, a corporation of Ohio

Application August 9, 1935, Serial No. 35,465

18 Claims.

(Cl. 148—8)

The invention relates to pickling apparatus and more particularly to apparatus for pickling pipes, rods and other elongate metal articles.

Experience has shown that in the pickling of metal, the best results are obtained by alternately submerging the material in an acid bath and exposing it to the atmosphere for at least as long a period as it is submerged in the bath. In the pickling of pipe and tubing the material should be tumbled within the bath as well as while exposed to the atmosphere to assist in removing the scale, and should be tilted within the bath as well as out of the bath to facilitate the flow and drainage of the acid, which action tends to remove scale from the inside of the pipe.

An object of the invention is to provide means for pickling pipe and the like whereby a group of pipes may be tumbled and tilted without as well as within the acid bath, the material being alternately submerged in the bath and removed therefrom, the periods during which the material is exposed to the atmosphere being at least as long as the periods during which the material is submerged in the bath.

Another object is to provide means whereby the material may be alternately tumbled in opposite directions as it is raised from and lowered into the bath, or by means of which it may be intermittently tumbled in the same direction on each upward or downward movement, or by means of which the material may be alternately raised and lowered without rotation or tumbling at any time during the operation.

A further object is to provide means whereby the material may be given substantially a complete rotation with each stroke of the apparatus and momentarily held stationary at the top of each upstroke.

The invention contemplates broadly the provision of pickling apparatus including a tank in which the acid bath is contained, a stand being located at each end of the tank, said stands being provided with vertically reciprocating rams having open bearings at their upper ends to receive a beam comprising an inner shaft arranged to be alternately rotated in opposite directions as the rams are raised and lowered and a tubular shaft arranged to be selectively connected to the inner shaft as by ratchet means whereby a variety of movements of the outer shaft may be obtained.

Sprockets or pulleys are carried by the tubular shaft and endless, flexible slings depend therefrom to carry the pipes or other elongate articles to be pickled. These sprockets or pulleys are preferably oppositely eccentrically mounted upon

the tubular shaft so as to alternately tilt the pipes in opposite directions as they are moved within and out of the bath.

The above objects together with others which may be later pointed out, or which will be obvious from the drawings and following description, may be attained by a construction as illustrated in the accompanying drawings, in which

Figure 1 is a vertical longitudinal section through a pickling apparatus embodying the invention showing the apparatus at the limit of the upstroke;

Fig. 2, a top plan view of the apparatus in the position shown in Fig. 1;

Fig. 3, a longitudinal sectional elevation of the apparatus showing the intermediate tilting positions;

Fig. 4, a sectional elevation showing the piping and valves for controlling the operation of the apparatus;

Fig. 5, a transverse sectional view through the apparatus showing the flexible slings in the lowermost position;

Fig. 6, a similar view showing the slings in the uppermost position;

Fig. 7, a transverse sectional view taken as on the line 7—7, Fig. 1;

Fig. 8, an enlarged detail section showing the pawl and ratchet mechanism for connecting the tubular sprocket shaft to the central shaft;

Fig. 9, a section on the line 9—9, Fig. 8;

Fig. 10, an enlarged section on the line 10—10, Fig. 8;

Fig. 11, a view similar to Fig. 10 of the opposite ratchet and pawl.

Similar numerals refer to similar parts throughout the drawings.

In the embodiment of the invention illustrated in the accompanying drawings, a tank 12 is provided, of any suitable construction and of a size 40 to conveniently accommodate a bundle of pipes, bars or other elongate material to be pickled. At each end of the tank is mounted a stand which may be in the form of a double A frame 13 rigidly supported at its base relative to the tank.

A vertical fluid cylinder 14 is mounted within a tubular housing 15 formed upon or fixed to the lower portion of each of the stands, and a vertically reciprocating ram 16 is operable within each cylinder, means to be hereinafter described being 50 provided for continuously reciprocating the rams.

Each ram 16 has a head in the form of a casting 17 fixed upon its upper end, as by a pin 18, and has a sleeve 19 attached thereto in any suitable manner and depending therefrom surround- 55

ing and spaced from the ram. A guide 20 is formed in each stand 13 to receive and guide the head of the ram as it is reciprocated therein.

Each of the heads 17 has an open or substantially U-shape bearing 21 formed in its upper end to receive the adjacent end of the lifting beam to be hereinafter described. A tubular felt washer 22 may be located in a suitable recess 21a in the lower end of each bearing 21 for the purpose of supplying sufficient lubrication to the bearing.

The lifting beam includes a central shaft indicated generally at 23 comprising the journal portions 24 which may be connected together by the central section 25 which may be tubular so that the reduced ends 26 of the journal portions may be inserted into the ends thereof and fixedly secured therein.

This central shaft is of sufficient length to permit the journal portions 24 thereof to be received into the open bearings 21 on the upper ends of the rams, and has a pinion 27 fixed to each end portion thereof and arranged to mesh with the vertical rack bar 28 formed upon or secured to the adjacent stand whereby the central shaft will be alternately rotated in opposite directions as the rams are raised and lowered.

The central shaft is surrounded by a tubular shaft 29 which may have reduced sections 29a secured within its end portions and journaled upon the central shaft as by means of an annular flange 30 which may be welded to the outer end of each section 29a as shown at 31. Each flange 30 is secured to the flange 32a of the bearing ring 32 as by means of bolts 33, a bushing 34 surrounding the adjacent journal portion 24 of the central shaft within said bearing ring 32.

A spaced pair of sprockets 35 is fixed upon the tubular shaft 29 and an endless, flexible sling, 40 which may be in the form of a chain 36, is suspended from each sprocket for supporting a bundle of pipes, rods or other elongate articles 37 to be pickled. These sprockets are preferably eccentrically mounted upon the tubular shaft in opposite positions as shown in the drawings, so as to produce an alternate longitudinal tilting of the bundle of pipes as the beam is raised and lowered.

A pair of loops or eyes 38 is fixed in spaced relation to the tubular shaft 29 to receive hooks from a crane or the like for transporting the beam from place to place in the mill and lowering it into or removing it from the bearings 21 of the rams. These loops or eyes are preferably angularly disposed as best shown in Fig. 2, so as to facilitate the insertion of the hooks therein.

For the purpose of operatively connecting the tubular shaft 29 to the central shaft, the oppositely disposed ratchet wheels 40 and 40a are fixed 60 near opposite ends of the central shaft. Pawls 41 and 41a are pivoted as at 42 and 42a, in the tubular shaft, adjacent to the ratchets 40 and 40a respectively.

A housing 43 may be formed for each of the 65 pawls and may be welded or otherwise attached to a suitable cut-out portion of the tubular shaft as indicated at 44, and provided with a removable cover 45 attached to the housing as by screws 46. A coil spring 47 may be provided for normally urging each pawl into engagement with the teeth of the corresponding ratchet wheel, one end of the spring being housed within a socket 48 formed in the cover 45 and the other end of the spring bearing against the flat face 49 of the 75 pawl.

An adjusting screw 50 may be located through a suitable screw threaded opening 51 in each cover for engagement with the outer end of the pawl to adjust the limit of movement of the same, and to hold the pawl out of engagement 5 with the ratchet if desired, a lock nut 52 being provided for holding the screw in adjusted position.

By means of the pawls and ratchets above described, a plurality of different movements of the tubular shaft may be obtained as desired. With both of the ratchets 40 and 40a engaged by their respective pawls, as shown in Figs. 10 and 11, the tubular shaft will be rotated counterclockwise, as viewed in Fig. 10, upon each upward movement of the beam, by means of the ratchet 40 and pawl 41, and through the ratchet 40a and pawl 41a the tubular shaft will be rotated clockwise upon each downward movement of the beam.

By disconnecting one or the other of the pawls from its respective ratchet, it will be seen that the tubular shaft will be intermittently rotated in one direction upon either the upstroke or the downstroke of the beam, depending upon which ratchet is disengaged. If both pawls are disengaged from the ratchets, then there will be no rotation of the tubular shaft as the beam is moved up and down, but the central shaft will continue to operate as a squaring shaft to synchronize the movement of the rams.

Any suitable means may be provided for reciprocating the rams 16, and for this purpose a hydraulic circuit may be provided which may be constructed in the manner shown in Fig. 4 of the drawings. Oil or the like may be stored in the tank, the upper portion of which is shown at 53.

A motor 54 may be provided for driving the pump 55 which is connected, by a feed pipe 56, to the tank. A baffle 57 may be located in the tank adjacent to the feed pipe to prevent undue turbulence in the tank and an air vent 58 of any conventional design may be provided. The delivery pipe 59 leads from the pump to the relief valve 60 which is connected by a return pipe 61 40 to the tank and by a pipe 62 to the four-way valve 63.

A return pipe 64 leads from the four-way valve to the tank, and may be connected to the return pipe 61 leading from the relief valve 60. A pipe 65 leads from the four-way valve 63 to the return pipe 64 and has provided therein a feed control globe valve 66. A pipe 67 leads from the four-way valve 63 to a T 68 from which the pipes 69 lead to the lower ends of the cylinders 14.

A time delay valve 70 may be provided in the circuit, being connected to the four-way valve 63 by a small tube 71, a similar tube 72 leading from the time delay valve to the tank. The pilot valve 73 is connected to the four-way valve 63 60 by means of a small tube 74, which tube is connected to the time delay valve by a similar tube 75. A small tube 76 leads from the time delay valve to the pilot valve and a similar tube 77 connects the pilot valve with the tube 72. A small 65 tube 78 leads from the pilot valve to the pipe 67.

The rotatable stem or plug 79 of the pilot valve is provided with a laterally spaced pair of angular fingers or arms 80 and 81 adapted to be engaged by the upper and lower dogs 82 and 83 70 respectively, mounted upon the sleeve 19 of one of the rams, the lower dog being preferably adjustably mounted thereon.

As shown in Fig. 4, the parts are at the top of the upstroke of the ram, at which time the 75

lower dog 83 has engaged the radial finger or arm 81 and tripped the pilot valve 73 directing the pilot pressure to the time delay valve 70. This time delay valve may be adjusted to provide for 5 a delay of from one to thirty seconds at the top of each upstroke.

After the expiration of the period for which the time delay valve is adjusted, the pilot pressure is transmitted to the right side of the four-way 10 valve 63 as viewed in Fig. 4, shifting the position of the four-way valve so that the pump delivery is discharged directly to the tank, at approximately zero pressure, while at the same time the cylinders are connected to the tank through 15 the feed control globe valve 66 which governs the rate of descent of the rams.

The rams may be stopped at the top of the stroke, for loading or unloading by shutting off the feed control valve 66. This valve may be shut 20 off at any time during the upstroke of the rams, and when the rams are stopped at the top of the stroke, the pump will be unloaded after the expiration of the period for which the time delay valve is set.

Assuming that the feed control valve 66 has not been shut off on the upstroke of the rams, the rams will start to descend as soon as the time 25 delay period has expired and as the rams reach the bottom of the downstroke, the dog 82 will engage the radial finger or arm 80, tripping the pilot valve 73, operating the four-way valve 63 so as to direct the pump delivery to the cylinders, raising the rams until the parts reach the top of the upstroke when the operation as above described will be repeated.

With the rams at the bottom of the downstroke, the bundle of pipes to be pickled is located within the pickling bath in the position shown in Fig. 5 and in broken lines in Fig. 1 40 and as the rams reach the top of the upstroke the bundle of pipes assumes the position shown in full lines in Fig. 1 and in Figs. 2 and 6. The intermediate positions of the bundle of pipes are shown in full and broken lines in Fig. 3.

As the rams travel upward about one-fourth of the upstroke the bundle of pipes will assume the position shown in broken lines in Fig. 3, being rotated and longitudinally tilted to the left and as the parts travel to about three-fourths of 50 the distance of the upstroke, the bundle of pipes will have been rotated, and longitudinally tilted in the reverse direction as shown in full lines in Fig. 3, thus not only assisting in tumbling the pipes against each other as they are rotated and 55 alternately raised from and submerged into the pickling bath, but also providing for facilitating the flow and drainage of the acid from the pipes as they are raised out of the bath, which tends to remove scale from the inside of the pipes.

With the apparatus constructed as above described, the rams will be continuously reciprocated, alternately raising the bundle of pipes from the pickling bath and submerging them therein, the bundle of pipes being rotated so as to tumble 60 the pipes against each other, and alternately tilted longitudinally in opposite directions during each raising and lowering movement. This tumbling and tilting is obtained by the rotation of the flexible slings which may alternate in direction or intermittently rotate in either direction as desired.

By means of the time delay valve, the bundle of pipes may be held at rest for a considerable period, at the top of each upstroke. The pipes are 75 thus alternately submerged in the acid bath and

exposed to the atmosphere for at least an equal period and with the construction provided the pipes may be exposed to the atmosphere for longer periods than they are submerged in the bath, thus obtaining the best results in pickling. 5

Although the drawings and above specification disclosed the best mode in which I have contemplated embodying my invention I desire to be not limited to the details of such disclosure, for, in the further practical application of my invention, 10 many changes in form and construction may be made, as circumstances require or experience suggests, without departing from the spirit of the invention, within the scope of the appended claims. 15

I claim:

1. Pickling apparatus including a tank containing pickling fluid, vertically reciprocating members mounted adjacent to opposite ends of said tank, an open bearing at the upper end of 20 each reciprocating member, a beam carried by the bearings of said reciprocating members, means for continuously reciprocating said reciprocating members, and flexible slings suspended from said beam for supporting material to be 25 pickled.

2. Pickling apparatus including a tank containing pickling fluid, vertically reciprocating members mounted adjacent to opposite ends of said tank, an open bearing at the upper end of 30 each reciprocating member, a beam carried by the bearings of said reciprocating members, means for continuously reciprocating said reciprocating members, means operated by the reciprocation of said reciprocating members for rotating said beam, and flexible slings eccentrically suspended from said beam for supporting material to be pickled.

3. Pickling apparatus including a tank containing pickling fluid, vertically reciprocating 40 members mounted adjacent to opposite ends of said tank, an open bearing at the upper end of each reciprocating member, a beam carried by the bearings of said reciprocating members, means for continuously reciprocating said reciprocating members, means operated by the reciprocation of said reciprocating members for rotating said beam, and flexible slings oppositely eccentrically suspended from said beam for supporting material to be pickled. 50

4. Pickling apparatus including a tank containing pickling fluid, vertically reciprocating members adjacent to said tank, a beam carried by said reciprocating members, means for continuously reciprocating said reciprocating members, flexible slings suspended from said beam for supporting material to be pickled, and cooperating means upon said beam and mounted adjacent to said reciprocating members for rotating said beam as the reciprocating members are reciprocated. 60

5. Pickling apparatus including a tank containing pickling fluid, vertically reciprocating members adjacent to said tank, a beam carried by said reciprocating members, means for continuously reciprocating said reciprocating members, flexible slings oppositely eccentrically suspended from said beam for supporting material to be pickled, and cooperating means upon said beam and mounted adjacent to said reciprocating members for rotating said beam as the reciprocating members are reciprocated. 65

6. Pickling apparatus including a tank containing pickling fluid, vertically reciprocating members adjacent to said tank, a beam carried 70

by said reciprocating members, means for continuously reciprocating said reciprocating members, flexible slings suspended from said beam for supporting material to be pickled, and cooperating means upon said beam and mounted adjacent to said reciprocating members for alternately rotating said beam in opposite directions as the reciprocating members are raised and lowered.

7. Pickling apparatus including a tank containing pickling fluid, vertically reciprocating members adjacent to said tank, a beam carried by said reciprocating members, means for continuously reciprocating said reciprocating members, flexible slings oppositely suspended from said beam for supporting material to be pickled, and cooperating means upon said beam and mounted adjacent said reciprocating members for alternately rotating said beam in opposite directions as the reciprocating members are raised and lowered.

8. Pickling apparatus including a tank containing pickling fluid, rams mounted at each end of the tank for continuously, alternately submerging material to be pickled in the fluid and removing it therefrom, and means cooperating with the rams for tumbling and longitudinally tilting the material within the fluid and while removed therefrom.

9. Pickling apparatus including a tank containing pickling fluid, rams mounted at each end of the tank, for continuously, alternately submerging material to be pickled in the fluid and removing it therefrom, and means cooperating with the rams for tumbling and alternately longitudinally tilting the material within the fluid and while removed therefrom.

10. Pickling apparatus including a tank containing pickling fluid, rams mounted at each end of the tank for continuously, alternately submerging material to be pickled in the fluid and removing it therefrom and maintaining the material out of the fluid for periods at least as long as it is submerged in the fluid, and means cooperating with the rams for tumbling and longitudinally tilting the material within the fluid and while removed therefrom.

11. Pickling apparatus including a tank containing pickling fluid, rams mounted at each end of the tank for continuously, alternately submerging material to be pickled in the fluid and removing it therefrom and maintaining the material out of the fluid for periods longer than it is submerged in the fluid, and means cooperating with the rams for tumbling and longitudinally tilting the material within the fluid and while removed therefrom.

12. Pickling apparatus including a tank containing pickling fluid, a stand at each end of the tank, a rack bar upon each stand, a vertically reciprocating member associated with each stand,

a rotatable beam carried by the reciprocating members, pinions upon said beam cooperating with said rack bars, and flexible slings suspended from said beam.

13. Pickling apparatus including a tank containing pickling fluid, a stand at each end of the tank, a rack bar upon each stand, a vertically reciprocating member associated with each stand, a beam including a central shaft carried by the reciprocating members, pinions upon said shaft cooperating with said rack bars, a tubular shaft journaled upon the central shaft, flexible slings suspended from said tubular shaft, and means for operatively connecting the tubular shaft to the central shaft.

14. Pickling apparatus including a tank containing pickling fluid, a stand at each end of the tank, a rack bar upon each stand, a vertically reciprocating member associated with each stand, a beam including a central shaft carried by the reciprocating members, pinions upon said shaft cooperating with said rack bars, a tubular shaft journaled upon the central shaft, flexible slings suspended from said tubular shaft, and ratchets and pawls for operatively connecting the tubular shaft to the central shaft.

15. Pickling apparatus including a tank containing pickling fluid, a stand at each end of the tank, a rack bar upon each stand, a vertically reciprocating member associated with each stand, a beam including a central shaft carried by the reciprocating members, pinions upon said shaft cooperating with said rack bars, a tubular shaft journaled upon the central shaft, flexible slings suspended from said tubular shaft, and oppositely disposed ratchets and pawls for operatively connecting the tubular shaft to the central shaft.

16. The method of pickling elongate material which consists in continuously, alternately submerging the material to be pickled into a bath of pickling fluid and removing it therefrom, and rotating, tumbling and longitudinally tilting the material within and out of the fluid.

17. Pickling apparatus including a tank containing pickling fluid, vertically reciprocating rams adjacent to opposite ends of the tank, a beam carried by said rams, flexible slings suspended from said beam for supporting material to be pickled, means for continuously reciprocating said rams, and means operated by the reciprocation of said rams for rotating said beam.

18. The method of pickling elongate material which consists in continuously, alternately submerging the material to be pickled into a bath of pickling fluid and removing it therefrom, and alternately oppositely rotating, tumbling and alternately oppositely longitudinally tilting the material within and out of the fluid.
